(57) **CLAIM**

The ornamental design for a golf cart plug, as shown and described.

DESCRIPTION

FIG. 1 illustrates a rear, top perspective view of a golf cart plug;

FIG. 2 illustrates a rear elevation of a golf cart plug;

FIG. 3 illustrates a front elevation view of a golf cart plug;

FIG. 4 illustrates a right side elevation view of a golf cart plug;

FIG. 5 illustrates a left side elevation view of a golf cart plug;

FIG. 6 illustrates a top plan view of a golf cart plug;

FIG. 7 illustrates a bottom plan view of a golf cart plug; and,
FIG. 8 illustrates a bottom, front perspective view of a golf cart plug.

The broken lines shown in FIGS. 1-3 and 6 of the drawings are for the purpose of illustrating portions of the golf cart plug that form no part of the claimed design.
